CLAIM

We claim the ornamental design for a media processing device, as shown and described.

DESCRIPTION

FIG. 1 is a front perspective view of a first embodiment of a media processing device, showing our new design;
 FIG. 2 is a rear perspective view thereof;
 FIG. 3 is a first side elevation view thereof;
 FIG. 4 is a second side elevation view thereof;
 FIG. 5 is a top view thereof;
 FIG. 6 is a bottom view thereof;
 FIG. 7 is a front elevation view thereof;
 FIG. 8 is a rear elevation view thereof;
 FIG. 9 is a front perspective view of a second embodiment of the media processing device;
 FIG. 10 is a rear perspective view thereof;
 FIG. 11 is a first side elevation view thereof;
 FIG. 12 is a second side elevation view thereof;
 FIG. 13 is a top view thereof;
 FIG. 14 is a bottom view thereof;
 FIG. 15 is a front elevation view thereof; and,
 FIG. 16 is a rear elevation view thereof.

The broken lines immediately adjacent the shaded areas depict the bounds of the claimed design, while all other broken lines are directed to environment. The broken lines form no part of the claimed design.

The wire frame lines shown throughout the views indicate surface contour.
